UNITED STATES PATENT OFFICE.

HARRY W. BOLENS, OF PORT WASHINGTON, WISCONSIN.

GRINDING-MACHINE.

SPECIFICATION forming part of Letters Patent No. 636,192, dated October 31, 1899.

Application filed April 22, 1899. Serial No. 714,007. (No model.)

To all whom it may concern.

Be it known that I, HARRY W. BOLENS, a citizen of the United States, and a resident of Port Washington, in the county of Ozaukee 5 and State of Wisconsin, have invented certain new and useful Improvements in Grinding-Machines; and I do hereby declare that the following is a full, clear, and exact description thereof.

10 My invention has for its main object to provide a simple economical high-speed grinding-machine especially designed for sharpening knife-sections of mower and reaper sickle-bars, but which may be readily converted into 15 a machine for grinding the ledger-plates of mower and reaper finger-bars, harrow-disks, and various other devices employed about a farm. Said invention therefore consists in certain peculiarities of construction and combination of parts hereinafter particularly set 20 forth with reference to the accompanying drawings and subsequently claimed.

Figure 1 of the drawings represents a perspective view of my improved grinding-machine; Fig. 2, an illustration that combines a 25 full-line partly-sectional showing, indicated by line 2 2 in the succeeding figure, and a dotted-line diagram of a grinding-wheel and its drive-gear when the machine is converted 30 from a grinder for sickle-bar knife-sections into a grinder for harrow-disks or finger-bar ledger-plates, the organization of the machine being such that said wheel and gear could not be made to appear in this showing except by 35 dotted lines; Fig. 3, a transverse section indicated by line 3 3 in the second figure; Fig. 4, a detail transverse section indicated by line 4 4 in said second figure, and Fig. 5 a detail plan view illustrating an inverted lower jaw 40 of a clamp constituting part of the machine.

Referring by letter to the drawings, A represents one and A' the other section of a rectangular frame constituting the base of my grinding-machine. Section A of the base- 45 frame is shown as having the ends of its side bars in the form of housings made to straddle and fit snugly on thickened pyramidal ends c of the side bars of the other section A', and these engaging ends of the side bars are bolted 50 together. By providing the housing b with longitudinal slots, as herein shown, provision is had for adjustable connection of the base-

frame sections, and the same result could be obtained by providing the pyramidal ends of the section A' with similar slots.

55

While I have shown and described a practical detachable and adjustable union of the base-frame sections, the same result may be obtained in various ways, and the main object of this construction is to provide for 60 knockdown shipment of the base and parts in connection therewith.

Whether made in sections or otherwise the base-frame is provided with a grooved cross-bar C adjacent to one of its ends and flush 65 with the upper edges of the sides. The groove in the aforesaid cross-bar is in a direction longitudinally of the base-frame, and engaging this groove is a triangular knife-edge rib d on the under side of a plate D, connecting a 70 pair of parallel standards E E', this plate and the standards being hereinafter sometimes designated by the term "standard-yoke." The sides of the base-frame and the standard-yoke are provided with opposing outer 75 lugs e e', bolted together, and owing to the engagement of the rib d with the groove in cross-bar C it will be understood that I provide for tilt adjustment of said standard-yoke.

The standard E has its inner end provided 80 with an eye for engagement of a pivot-stud f, extending inward from a link F, and the other standard E' is provided with a pivot-stud f', extending through an eye in the inner end of a link F', spring keys or pins being engaged 85 with said studs against washers to prevent displacement of said links. The links are connected by a bar G, the three parts being in one casting, and the bar is provided with a central eye g for a handle H, this handle 90 and said eye being tapered to provide for wedging fit of one within the other. As herein shown, the handle-eye is formed by a series of loop-swells alternately upon opposite sides of the bar G on successive parallel planes, as 95 seen in Figs. 1 and 3. Therefore the mold for the rocker-yoke embracing said bar and aforesaid links does not have to be cored.

The standard E is provided with a lateral outer lug h, and a hook-latch i in pivotal connection with a lug-opposing stop-arm i' of link F is caught on said lug when the rocker-yoke is swung into the position indicated by dotted lines in Fig. 1 and shown by full lines in Fig.

2, in which last-named figure the engagement of said lug *h* and hook-latch *i* is shown in dotted lines.

The outer end of link *F* is provided with an eye for the engagement of a pivot-stud *j*, projecting inward from a side bar *I* of a skeleton-frame carrier, and an opposing side bar *I'* of this carrier is provided with an eye engaged by a stud *j'*, extending inward from the outer end of link *F'*, spring keys or pins being engaged with said studs against washers to prevent displacement of the carrier.

Loose on a stud-reduction *j''* of a boss *J* of link *F'* in line with stud *j'* is the outwardly-extended hub of a sprocket-wheel *K*, and this hub is provided with a series of radial cogs to form a pinion *L* in mesh with a spur-wheel *M*, having a handle *M'*, this spur-wheel being loose on a stud *k*, extending outward from a branch *E''* of standard *E'*, these wheels being held in place on the bearing-studs by spring keys or pins in opposition to interposed washers.

The standard *E'* and its branch *E''* form a yoke in which clearance is had for the rotation of sprocket-wheel *K* and the run of a link belt *N* engaged therewith, this link belt being also engaged with a sprocket-pinion *O*, fast on an arbor *P*, that has its bearings in the side bars of the carrier above specified, these bars being joined by a brace-bar *I''*, as best illustrated in Fig. 1. The arbor *P* extends outward from each side bar of the carrier and has its ends reduced to form annular abutments, and these reduced ends of said arbor are screw-threaded. A grinding-wheel may be held on each reduced end of arbor *P* against an abutment of the latter by means of a clamp-nut, and for convenience one such wheel *Q* is shown on one end of said arbor in Fig. 1.

Between the side bars of the carrier a grinding device *R* for sickle-bar knife-sections is made fast on arbor *P*, and as the grinding-wheel *Q* or substitute for same is intended for grinding harrow-disks, finger-bar ledger-plates, or tools of various kinds each machine furnished to the trade will be accompanied with a complement of grinding-wheels designed for various grinding operations, any one of said wheels being attachable to either end of said arbor.

As herein shown, the standard *E* is provided with a lug *u*, to which one end of a spiral tension-spring *S* is connected, and the other end of this spring is hooked on a lug *m* of the carrier when the latter is in the position shown in Fig. 1, the machine being then organized for grinding sickle-bar knife-sections, the arbor *P*, with the grinding device *R* thereon, being driven at high speed by the gearing above specified. It would be practical to connect one end of spring *S* to the rocker-yoke instead of the standard-yoke.

65 Constituting the lower jaw of a sickle-bar clamp is a plate *T*, having a semispherical depending lug *p*, midway of its width, engaging

a socket-bracket *q* upon the inner side of an end of the base-frame forward of the parts previously set forth, and another depending lug *r*, adjacent to that edge of the plate farthest from the former lug, rests upon a cross-bar *s* of said frame. The length of the lug *r* is such that the plate *T* has inclination in an upward direction toward the standard-yoke, and said plate and side bars of the base-frame are provided with opposing lateral lugs *t*, bolted together, the bolt-openings in lugs *t* being curved slots, so that the aforesaid plate may have a certain amount of rotary as well as tilt adjustment, the semispherical lug *p* and socket-bracket *q* constituting a ball-and-socket joint that permits of such adjustments. Plate *T* is provided upon its upper side with triangular ledges *u*, that serve as rests for knife-sections of a sickle-bar, and in pivotal connection with a lug extension *v* of said plate is the other jaw *T'* of the clamp for said sickle-bar, a set-nut *w* being run on the screw-threaded upper end of a post *x*, that constitutes the pivot for the latter clamp-jaw.

By having the clamp in pivotal and tilt adjustment on the base-frame and the standard-yoke also in tilt adjustment on said frame the machine may be set very fine for work on sickle-bar knife-sections, and said base-frame being in sections adjustably connected, as herein set forth, said machine is capable of a still finer setting for the same kind of work.

The machine being organized, as shown in Fig. 1, with the grinding-wheel *Q* omitted, the spring-controlled carrier is manipulated by its handle *H* to bring grinding device *R* on and off knife-sections of a sickle-bar held by the clamp.

For sharpening harrow-disks or finger-bar ledger-plates a grinding-wheel designed for the work is made fast on an end of arbor *P*, and the spring *S* being disconnected from the carrier the latter and the rocker-yoke in connection therewith are swung over back of the standard-yoke, said rocker-yoke being held in approximately horizontal position by engaging its latch *i* with the lug *h* of said standard-yoke, and the grinding-wheel is brought on and off the disk or plate to be ground by manipulation of said carrier, it being understood that the grinding is done on the aforesaid disk or plate without detaching the same from the machine of which it forms a part.

From the foregoing it will be understood that the machine above specified may be converted from a grinder of one kind into that of another without taking apart, and being accompanied by a suitable complement of grinding-wheels it may be utilized to sharpen a great variety of implements and tools common about a farm, any one of the several grinding-wheels being put on or taken off the arbor *P* without the aid of any tool other than an ordinary monkey-wrench, and the same may be said regarding the assembling of said machine shipped knockdown from the factory.

As shown in Fig. 2, the base-frame of the machine may be provided with apertured lugs *y* for engagement of screws or bolts employed to connect said machine with a bench or other support.

Having thus described my invention, what I claim as new, and desire to secure by Letters Patent, is—

1. The horizontal rectangular base-frame in two sections, one section having the ends of its side bars thickened and of pyramidal contour, the opposing ends of the other frame-sections being in the form of housings in straddle fit upon said side bar ends of the former frame-section, and means for maintaining the union of said frame-sections.

2. The rocker-bearing standard-yoke, the adjustable sickle-bar clamp, the rocker-yoke in connection with said standard-yoke, the carrier in pivotal connection with the rocker-yoke, the grinding device rotative between side bars of said carrier, driving mechanism for said grinding device, and the tension-spring for the aforesaid carrier.

3. The horizontal base comprising sections in longitudinally-adjustable connection, the rocker-bearing standard-yoke, the adjustable sickle-bar clamp, a rocker-yoke in connection with said standard-yoke, the carrier in pivotal connection with the rocker-yoke, the grinding device rotative between side bars of said carrier, driving mechanism for said grinding device, and the tension-spring for the aforesaid carrier.

4. The rocker-yoke in connection with standards, the carrier in pivotal connection with said rocker-yoke to be swung forward or back of the standards, means for holding the rocker-yoke stationary in approximately horizontal position back of said standards, the grinder-arbor mounted in said carrier, and the drive-gear for said arbor.

5. The standard-yoke in rocker-bearing on the base, the rocker-yoke in connection with said standard-yoke, the carrier in pivotal connection with said rocker-yoke to be swung

forward or back of the standard-yoke, means for holding the rocker-yoke stationary in approximately horizontal position back of the aforesaid standard-yoke, the grinder-arbor 50 mounted in said carrier, and the drive-gear for said arbor.

6. The standards, one of which is provided with a branch that therewith constitutes a yoke, the rocker-yoke in connection with said standards, a carrier in pivotal connection with the rocker-yoke, the sprocket-wheel carried by said rocker-yoke, the pinion integral with the sprocket-wheel, the driving spur-wheel mounted on an outer stud of said standard branch 60 and in mesh with said pinion, the grinder-arbor mounted in the carrier and provided with the sprocket-pinion, the link belt arranged on said sprocket-wheel and sprocket-pinion to run in the yoke of which the aforesaid standard branch forms a part, and means for holding the aforesaid rocker-yoke in approximately horizontal position back of the aforesaid standards.

7. The rocker-yoke in connection with 70 standards, the carrier in pivotal connection with the rocker-yoke to be swung forward or back of said standards, means for holding said rocker-yoke in approximately horizontal position back of the standards, the arbor mounted 75 in the carrier and extended therefrom for attachment of a grinding-wheel, the grinding device for sickle-bar knife-sections permanent on said arbor between side bars of said carrier, the drive-gear for the arbor, the sickle-bar clamp arranged forward of said standards, 80 and the tension-spring attachable to the aforesaid carrier.

In testimony that I claim the foregoing I have hereunto set my hand, at Milwaukee, in 85 the county of Milwaukee and State of Wisconsin, in the presence of two witnesses.

HARRY W. BOLENS.
